UNITED STATES PATENT OFFICE.

JOHN H. HARDCASTLE, OF EDENWOLD, TENNESSEE.

MILK-CAN.

1,203,730.

Specification of Letters Patent.

Patented Nov. 7, 1916.

Application filed November 24, 1915. Serial No. 63,157.

To all whom it may concern:

Be it known that I, JOHN H. HARDCASTLE, a citizen of the United States, residing at Edenwold, in the county of Davidson and State of Tennessee, have invented certain new and useful Improvements in Milk-Cans, of which the following is a specification, reference being had to the accompanying drawings.

10 This invention relates to certain improvements in milk cans and similar containers and has for its primary object to provide a simply constructed and durable container of this character whereby the contents there-
15 of may be maintained at a relatively low temperature and spoiling of the same is obviated.

It is another object of the invention to provide a refrigerating container of the above 20 character having an inner liquid receiving receptacle, and an outer receptacle or shell spaced from said inner receptacle, whereby ice may be packed around the inner receptacle, and means for withdrawing the contents of the inner receptacle and also draining 25 the water from the ice chamber.

With the above and other objects in view, my invention consists in the novel features of construction, combination and arrangement of parts to be hereinafter more fully described, claimed and illustrated in the accompanying drawing, in which,

Figure 1 is a vertical sectional view through a milk can constructed in accordance with the present invention; Fig. 2 is a detail prospective view of the top section of the can; and Fig. 3 is a detail horizontal section taken on line 3—3 of Fig. 1.

Referring in detail to the drawing, 5 40 designates the outer shell or casing, to the lower edge of which a circumscribing cast metal ring 6 is riveted or otherwise permanently fixed and projects below the lower edge of the shell wall. Within the lower 45 end of said shell, the concavo-convex bottom plate 7 is secured. Upon the upper end of the shell 5, the tapering frusto-conical head section 8 is permanently secured and, at its smaller end, is formed with the 50 upstanding flange 9. Upon the head section 8 at diametrically opposite points, suitable handles 10 are secured.

12 designates the inner fluid containing receptacle which is provided in its lower end 55 with the concavo-convex bottom plate 13

disposed in substantially concentric relation to the bottom plate 7 of the outer shell 5. A ring or annulus 14 rests upon the outer edge of this bottom plate and is inwardly bent at diametrically opposite points and 60 provided with upwardly extending lugs 15 which are bolted or otherwise rigidly fixed to the lower end of the receptacle 12. The upper end of this inner receptacle is also provided with a frusto-conical head section 65 16 having a relatively long upstanding flange 17 formed upon its smaller end. A filling tube 18 extends downwardly through the flange 9 and the flange 17 and is preferably permanently fixed to said annular flanges. 70 The upper end of this tube, projecting above the flange 9, is formed with an outwardly flaring or funnel-shaped mouth 19.

20 designates a removable cap having a funnel-shaped body portion and a tubular 75 extension 21 on its smaller end, said extension being closed at its extremity by the concavo-convex end wall 22. Within the funnel-shaped body of the cap and to diametrically opposite sides thereof, a suitable 80 handle 23 is secured. This cap and the flaring end wall 19 of the tube 18 are provided with openings indicated at 24, which are adapted to register to receive the shackle of a padlock, whereby said cap may be 85 securely locked in place and access to the contents of the receptacle 12 prevented.

The wall of the head section 8 of the outer shell 5 is provided at diametrically opposite points with threaded openings, in 90 which the closures indicated at 25 are adapted to be removably engaged.

26 designates a faucet which extends through the outer shell 5 and through the wall of the inner receptacle 12, whereby 95 the contents of the latter may be withdrawn. A second faucet 27 is also connected to the lower end of the shell 5 so as to drain water therefrom.

In the use of the invention, it will be understood that the cap 20 is removed and the inner receptacle 12 filled with the milk or other liquid. The caps 25 are then removed and ice inserted into the space between the walls of the shell 5 and receptacle 100 12 through the openings in the head section 8 of said shell. By the provision of the ring 14 which spaces the lower edge of the container 12 from the bottom wall 7 of the outer shell, particles of ice will also enter 110

the space between the concavo-convex bottom walls 13 and 7. Thus, the entire space between the corresponding walls of the container and the outer shell can be packed 5 with ice so that the contents of the inner receptacle will be maintained at a low temperature. It will, of course, be understood that the inner receptacle may be of any desired diameter and capacity and the space 10 provided for the packing of the ice varied as may be desired.

It will thus be seen that I have produced a very simple, serviceable and convenient container for milk and like fluid commodities which can be manufactured and sold 15 at comparatively small cost.

While I have shown and described the preferred construction and arrangement of the several features of the device, it is to be understood that the same is susceptible of considerable modification therein and I, therefore, reserve the privilege of resorting 20 to all such legitimate changes as may be

fairly embodied within the spirit and scope of the invention as claimed.

Having thus fully described my invention, what I desire to claim and secure by Letters Patent is:—

A container of the class described including an outer shell, an inner receptacle concentrically spaced from the wall of said shell, and a ring or annulus laterally spaced from the lower edge of the receptacle and tightly engaging against said outer shell, said annulus being offset at spaced points 30 and fixed to the wall of the receptacle, said ring or annulus projecting below the bottom of the receptacle to support said receptacle with its bottom wall in spaced relation to the bottom wall of the shell.

In testimony whereof I hereunto affix my signature in the presence of two witnesses.

JOHN H. HARDCASTLE.
